(57) **CLAIM**

The ornamental design for a protective cover for LED flashlight, shown and described.

DESCRIPTION

FIG. 1 is a front elevational view of the invention;
FIG. 2 is a rear elevational view of the invention;
FIG. 3 is a right-side elevational view of the invention;
FIG. 4 is a left-side elevational view of the invention;
FIG. 5 is a top view of the invention; and,
FIG. 6 is a bottom view of the invention.
The broken line showing in FIG. 1 is for unclaimed structure
only and forms no part of the claimed design.
